UNITED STATES PATENT OFFICE.

FRITZ ERNST, OF ZURICH, SWITZERLAND.

DEVICE FOR THE TREATMENT OF AFFECTIONS OF THE AIRWAYS OF THE HUMAN BODY.

Application filed March 17, 1922. Serial No. 544,504.

To all whom it may concern:

Be it known that I, FRITZ ERNST, a citizen of the Swiss Confederation, residing at Weststrasse No. 52, Zurich, Switzerland, have invented new and useful Improvements in Devices for the Treatment of Affections of the Airways of the Human Body, of which the following is a specification.

The present invention relates to a new and improved device for the treatment of affections of the airways of the human body. The main object of the invention is to provide a simple and inexpensive device which produces hot air, which air is introduced by aspiration into the airways.

Other objects of the invention relate to the construction of the device which are more fully described in the annexed specification.

20 In the drawings forming part of the specification Fig. 1 is a sectional elevation of the device.

Fig. 2 is a cross-section on line A—B of Fig. 1.

25 Fig. 3 is an end view of the device and

Fig. 4 shows the connection of the electrical resistances in a diagrammatical manner.

The device shown in the drawing comprises a tube 1 lined on its inside with tubular layer 2 of insulating material. At one end the layer 2 is provided with an inwardly projecting flange 3, the other end is provided with a cover 4. In the cover 4 and the flange a tube 5 is fixed. Between the layer 2 and the tube 5 there is a space 6 through which air passes entering through holes 7 and passing through holes 8 into tube 5. Within the tube 5 a number of disks 9 are arranged. The disks 9 are fixed on a spindle 10 by means of nuts 11; the spindle 10 is screwed into the cover 4. Each disk 9 is provided with a number of holes 12 and on the disks electrical resistance coils 13 are fixed. The resistances are connected to three

split-pins 14, 15, 16 fixed to the cover 4 in the manner shown in Fig. 4. In the tube 5 a mouth piece 17 of glass is fixed in which a disk 18 of fine wire gauze is fixed, said disk being easily removable. In the mouth piece 17 humidified or medicated fibres, cotton, etc., may be loosely arranged through which air may be drawn. The pins 14, 15, 16 are arranged with reference to each other in such a manner that the plug 20 which is connected to the live wires may be brought on the plugs 14, 15 or 14, 16. If the plug is put on the pins 14, 15 all the resistances are brought in circuit, if the plug is fixed on the pins 14, 16 only half of the resistance is brought in circuit.

The piece 17 is taken in the mouth and air is drawn in which by passing along the heated resistances is heated and enters the air ways in heated condition (about 30 to 60° C.) The heated air has a marked heating effect by bronchitis, inflammations, etc. The heated air by passing through the piece 17 evaporates water, etc., with which the cotton, etc., has been soaked.

Also I have described the preferred form of construction. I wish it understood that various changes may be made without departing from the spirit of the invention.

What I wish to secure by U. S. patent is:

A device for the treatment of affections of the airways comprising an outer tube, having perforations, a perforated inner tube in the outer tube and the wall of which is spaced from the wall of the outer tube, a mouth piece connected to one end of the outer tube and extending into the corresponding end of the inner tube, a closure for the opposite end of the inner tube, resistances arranged in the inner tube and having supporting means attached to the closure, and electrical conductors also attached to the closure and connected to said resistances.

In witness whereof I affix my signature.
FRITZ ERNST.
